(57) CLAIM

The ornamental design for an automobile and/or other replicas, as shown and described.

DESCRIPTION

FIG. 1 is a front elevational view of the automobile and/or other replicas showing my new design;

FIG. 2 is a rear elevational view thereof;

FIG. 3 is a top plan view thereof;

FIG. 4 is a right side elevational view thereof;

FIG. 5 is a left side elevational view thereof;

FIG. 6 is a front perspective view thereof as seen from the right side; and,

FIG. 7 is a rear perspective view thereof as seen from the right side.

The broken lines illustrate environmental structure only and form no part of the claimed design.
